UNITED STATES PATENT OFFICE.

JOHN SHELLENBERGER, OF CHICAGO, ILLINOIS.

MACHINE FOR MAKING WIREBOUND BOXES.

Application filed April 30, 1926. Serial No. 105,715.

This invention pertains to machines for making wire bound boxes, and more particularly for making boxes with binding wires which have eyes twisted at each end.

5 A form of these wire bound boxes is fully disclosed in my Patent No. 1,033,833, issued July 30, 1912.

The wire bound boxes in common use have the ends of the binding wires extended above the front side of the box, and have the other ends extending beyond the edge of the lid of the box. After the box is filled for shipment, these ends of the binding wires are twisted together; and when the consignee 15 opens the box the wires are cut, which ruins the box so that it cannot be readily fastened again. Considerable money is lost in this way every year. Twisting eyes on the ends of the binding wires is not new, but I know 20 of no machine that can successfully staple the box blanks; neither do I know of any machine that has been successful in manufacturing wire bound boxes with the edges of the box boards bevelled for the purpose 25 of securing a tight box.

One known and ordinary method of manufacturing wire bound boxes is by using forms or frames that travel on rails which carry the assembled box boards through the stapling machine while the binding wires are being stapled on such boards; but in such method the forms have heretofore been carried by hand from the rear of the machine around to the front to be again passed 30 through the machine with another box blank thereon, and it is apparent that where the box blank is large, up to sixteen feet long, it is expensive and impractical; and furthermore each size box requires a different size 35 form in such known method of manufacture, thus producing an additional expense.

One object of my invention is to provide a form or frame that can be quickly adjusted to accommodate various size boxes.

40 A further object is to provide means or mechanism by which the travel of the form is automatically reversed, making the form travel through the stapling machine while stapling one blank, and then returning the form thru the stapling machine while 45 stapling another box blank. While stapling the box blank it is fed by a step by step movement so as to give the staples time to pass through the box board. This has heretofore been done by a rack-bar actuated by a 50 crank or an eccentric which is driven at the

same speed as that of the main drive shaft so as to time properly with the staple driver; and the rack-bar thus driven, moves the box form during about one-third of the revolution of the drive shaft, thus giving the form a jerk or quick movement as it starts, which is liable to disarrange the box boards positioned on said form, especially if the box boards are bevelled so as to overlap. Consequently one object of my invention is to overcome this defect and to provide pawls and means for imparting to the form or frame a movement which starts gradually and slowly, using more than three-fourths of the revolution of the main shaft to drive one step of the form, but by which the pawls are returned instantly for the next gradual movement of said form. Another object is to provide means, preferably in the form of 70 holding bars, for holding the box boards in position when assembled in the form, so that the boards will remain in position, however much warped they may be, and to prevent the bevelled edges of the boards from crawling over each other.

A further object of my invention is to provide means for quickly placing and drawing taut the binding wires that have eyes twisted on each end, preferably by providing adjustable members with hooks for receiving said eyes, and means for making all the binding wires taut simultaneously, so that staples being driven, will straddle the wires without missing. Another object of 80 my invention is to provide a rack-bar with blocks on which teeth are placed away from the center so that should a staple come between box boards, the block with its tooth can be reversed so as to bring the staples 85 away from the edge and fully on the box board.

These objects and other objects and advantageous ends are accomplished with my invention, as will become apparent from the 100 following description taken in connection with the accompanying drawings, in which,

Fig. 1 is a side view of a stapling machine with my invention applied thereto;

Fig. 2 is a plan view of my improved 105 form or frame, which constitutes part of the present invention;

Fig. 3 shows a vertical cross section of a machine with my form or frame thereon, parts being broken away;

Fig. 4 is a vertical sectional view taken on line 4—4 of Fig. 3, with parts broken away;

Fig. 5 is a vertical sectional view taken on line 5—5 of Fig. 2;

Fig. 6 is a perspective view of my reversible block with a tooth off center thereon, 5 forming a part of the rack-bar;

Fig. 7 is a side view of the mechanism for advancing the form in reverse directions;

Fig. 8 is a plan view thereof;

Fig. 9 is a detail view showing the 10 advance of reversing a block in the rack-bar, so as to avoid driving a staple between the box boards and

Fig. 10 is a detail view showing the 15 upwardly swingable board holding bar, and the laterally adjustable side rail on the form or frame.

In the drawings I have shown my invention in connection with a stapling machine which includes upright members or standards 12 with a cross member or beam 13 at the top and longitudinal track members or supporting rails 14 mounted thereon, with bolts 15 or the like. Suitable stapling members or devices 16 are mounted in proper positions on the machine, in the usual manner, to drive the staples into the box boards and fasten the binding wires thereon.

My improved form or frame comprises end beams or rails 20 and 21, and side beams 30 or rails 22 and 23 fastened thereon, said side beams having bottom grooves 24 slidable on ribs 25 provided on track members 14. On each side beam or rail is mounted a rack-bar which includes a pair of bars 27, fastened on the beam with bolts 28 or the like, and being bevelled at the adjacent sides to provide a groove which is contracted at its upper edge; and in each groove are movably and reversibly mounted bevelled blocks 29 each having a tooth 30 thereon offset from the center of the block and preferably integral therewith. These blocks are fastened in position by a set screw 31 or the like, and are reversible in said groove to bring any tooth in a different relative position on the rack-bar.

I also provide means for adjusting the form or frame for its length and width so as to accommodate the various size box blanks, and this means includes an auxiliary side rail 32 adjustably mounted on the end rails 20 and 21 (see Figs. 2 and 10), as by the use of an angle iron 33 having a slanting lower flange 34 which draws the end rail 55 and auxiliary rail together with increasing firmness as the fastening screw 35 draws the angle iron against the auxiliary rail. This means for adjusting the size of the form also includes a cross rod 36 fastened on brackets 37 and 38 which are mounted on the rack-bars, by the use of bolts 39 extending from blocks 29, or in any suitable manner. Collars 40 are adjustably mounted on said rod, by set screws 41, and have hooks 42 for receiving the eyes 43 provided at the ends of

binding wires 44. Hooks 45 are also provided on the end rail 21 to receive the eyes at the other ends of said wires 44, and these hooks are threaded into said rail in the positions desired, thus making both sets of 70 hooks adjustable laterally on the form or frame to suit the particular size of box blank and the particular number of binding wires used.

The means for drawing and holding all 75 the binding wires taut simultaneously includes an operating handle 46 fastened on said rod 36, and carrying a pawl 47 which engages a ratchet segment 48 fastened on said bracket 38 to hold said rod and wires in 80 position.

I also provide means for holding the box boards 49 firmly in position while the staples 50 are driven therein to fasten the binding wires on said boards, and such means includes a holding bar 51 swingably mounted with hinge arms 52 on hinge plates 53 fastened on bolts or stems 54 provided on bevelled blocks 55 held at the ends of the grooves formed between rack-bars 27, and by set screws 31. A holding bar 56 is swingably mounted with hinge arms 57 on hinge plates 58 which are fastened on the auxiliary side bar 32, with bolts 59 or the like. Teeth 51' and 56' are preferably provided on bars 51 and 56 respectively to engage into the box boards and hold them firmly in the proper positions on the inwardly extending portions of side rail 22 and of auxiliary rail 32.

Means or mechanism is provided for operating the form or frame and giving it a steady step by step movement through the machine, and this means comprises a pair of oppositely arranged levers 61 and 62 pivoted on standards 12 of the machine frame and carrying respectively pawls 63 and 64 on pivot pins 65 and 66. Springs 67 and 68 normally press said pawls down to engage teeth 30 on the rack-bar. The levers are curved at the lower parts 61' and 62' and each preferably has a bearing plate or tip 69 at the end. An eccentric disc or wheel 70 is mounted on the usual drive shaft 71 of the machine and may be driven in any suitable manner; and preferably the edge or perimeter of this disc or wheel is made eccentric, having a short surface or space 70' with an even or regular curvature, then extending gradually, spirally outward providing an increasing radius up to a point 70'' where it drops abruptly inward to the short surface or space 70'. A rod 72 is held in a bracket 73 on standard 12 and extends through slots 74 in the levers, while coil springs 75 on said rod normally move the levers and pawls apart and hold the bearing tips 69 against the eccentric edge or perimeter of wheel 70.

With this arrangement of levers, pawls 130

and eccentric wheel, the travel of tips 69 on the space 70', of regular curvature, effects a temporary period of rest of the lever and its pawl which is in engagement with the 5 rack-bar, thus making sure that said rack-bar and form stand still at the moment the stapling machine drives the staple on to the wires into the board; and with the gradual outward curvature of the perimeter, the 10 form and the supported box boards are gradually and steadily advanced until the tip 69 drops from point 70" down to the space 70', and the active lever then idly returns the 15 pawl back of the succeeding tooth 30 for the next forward movement of the form and supported box boards, thus giving the form and boards a gradual and steady step by step movement through the machine.

Means is provided for automatically reversing the form operating mechanism and for moving said form in two opposite directions through the machine, and this means comprises a pawl releasing member or bar 76 with a raised part or cam 77 thereon to be moved alternately under the side pins or pegs 78 and 79 provided on pawls 63 and 64, for raising either one of these pawls out of its operative position, while the opposing companion pawl engages 20 the rack-bar and operates the form and box boards. The bar 77 is slidably supported in brackets 80 on the track members 14. A swingable arm or lever 81 is fulcrumed on a pin 82 mounted on the standard 12, and is provided with a rib 83 which is engaged by pins 84 extending outwardly from rack-bars 27, consequently swinging the lever 81 and moving it against pins 85 which extend outwardly from the pawl releasing bar 40 76, and thereby automatically moving said bar and its cam 77 so as to lift one pawl into inoperative position and drop the other pawl into operative engagement with the rack-bar. Springs 86 tend to return and retain lever 81 in its central or neutral position. An index finger 87 is also provided on the rack-bar of the form to co-operate with a notch or mark 88 on track member 14, for setting the form in the proper position on 45 the machine so that the staples are driven in the proper and desired position on the boards.

What I claim as my invention and desire to secure by Letters Patent is:

55 1. A boxblank making machine comprising a form for assembling box boards, means for quickly adjusting said form to the desired size of boxblank, means on the form for holding binding wires in position 60 to be attached to the box boards, and means for operating said form so as to permit the stapling of the binding wires to the box boards to form a wire bound boxblank while the form is traveling through the machine in either of two opposite directions.

2. A box making machine comprising a form arranged for assembling box boards thereon, said form including an auxiliary side member and an auxiliary end member, both being adjustable to suit the required size of the box and provide a complete form within the machine, wire engaging means on said auxiliary end member, and means for revolving said end member to tighten the wires engaged by the means thereon. 75

3. A box making machine comprising a form for assembling box boards thereon, hinged bars extending longitudinally of said form arranged to be swung outward while boards are being assembled, and then swung back on the box boards and having means for engaging and positively holding the boards and prevent them from sliding over each other. 80

4. A box making machine comprising a form for assembling box boards thereon, and hinged bars extending longitudinally of said form arranged to be swung outward while the boards are being assembled, and teeth on said bars to engage the boards when the bars are swung inward, and to prevent boards with joining bevelled edges from creeping over each other during the movement of said form. 85

5. A box making machine comprising a form on which to assemble box boards, the form having a movable auxiliary end rail, and adjustable collars on said rail having hooks to hold binding wires. 90

6. A box making machine comprising a form on which to assemble box boards, said form having an auxiliary end rail, collars on said rail with hooks to hold binding wires, and means for turning said rail for simultaneously drawing the binding wires 105 taut. 100

7. A box making machine comprising a form on which to assemble box boards, mechanism including oppositely arranged operating means, each including a pawl continuously operative while the form is being fed in one direction and so arranged as to remain idle while the form is being fed in the opposite direction, and a 110 slideable bar with cam means for retracting the pawl in operation and to release the opposite pawl to cause travel of the form in the opposite direction. 115

8. A box making machine comprising a form for assembling box boards, oppositely arranged means for operating the form in opposite directions, and means for setting said operating means by placing said form in its operative work assembling position on said machine, thereby assuring the movement of said form in the desired direction. 120

9. A box making machine comprising a form for assembling box boards, mechanism for operating said form and including a rack-bar with oppositely arranged pawls 125 130

for coaction therewith for feeding the form in opposite directions, and means for releasing one of said pawls by placing the form in its operative position beneath the staplers 5 on the machine, thereby assuring the travel of said form in the desired direction.

10. A box making machine comprising a form for assembling box boards, a rack-bar and pawls for operating the same, one pawl 10 being continuously operative during the making of a complete boxblank and the other pawl idle, a trip-bar for retracting the pawl in operation, and a swingable arm and means for actuating said trip-bar 15 whereby the other pawl may be brought into operation to cause the travel of said form in a reverse direction.

11. A box making machine comprising a form for assembling box boards, a rack-bar 20 on said form, oppositely operating pawls for actuating the rack-bar, a trip-member with cam means for releasing one of said pawls, and an arm with means thereon for actuating said trip member through the 25 movement of said form into its operative position on the machine.

12. A box making machine comprising a form for assembling box boards, a rack-bar on said form, pawls for actuating said rack-bar in opposite directions, a trip member with means for releasing either one of said pawls, an arm with means for actuating said trip member, and means projecting from the rack-bar for actuating said arm to 30 operate the trip member and release one pawl when the form is moved into its operative position on the machine.

13. A box making machine comprising a form for assembling box boards, mechanism including oppositely operating pawls and 40 levers to actuate said form, and an eccentric wheel with a spiral rim for operating said levers and pawls to give the form a step by step movement.

14. A box making machine comprising a form with a rack-bar, oppositely arranged pawls for operating said rack-bar in opposite directions, levers for moving said pawls, and an eccentric wheel with a spiral perimeter for operating said levers and pawls 50 with a gradual motion to give the form a steady, step by step movement.

15. A box making machine comprising a form for assembling box boards thereon, mechanism for feeding said form in opposite directions including oppositely operating pawls, lever means for operating said pawls, and an eccentric spiral rimmed wheel 55 for operating said lever means, said wheel having an innermost portion which is so disposed as to be within the arc of a circle having its center coinciding with the axis of the wheel whereby to provide a dwell in the movement of the form so that the form may remain stationary while staples are being inserted, an eccentric portion extending outwardly from this annular portion so as to cause the form to have a slow feeding movement, and a sudden drop between the 60 end of said eccentric portion and said annular portion.

In testimony whereof I have signed my name to this specification.

JOHN SHELLENBERGER.
